UNITED STATES PATENT OFFICE

2,448,203

POWDER TESTER

Alfred Africano, Cumberland, Md., assignor to the
United States of America as represented by the
Secretary of War

Application January 18, 1946. Serial No. 641,904

5 Claims. (Cl. 73—35)

1

This invention relates to powder testers and more particularly to shear-disk powder testers for obtaining partially burned samples of relatively large size powder grains.

The conventional shear-disk tester used for making such tests consists essentially of an elongated cylindrical chamber having a conventional copper-ball pressure gage secured by means of an adapter at one end and a nozzle for the discharge of gases generated by the burning propellant at the other end. The nozzle is screwed into the end of the cylinder, thereby securing a shear-disk in location, the thickness of which determines the limit to which chamber pressure can increase before shearing of the disk and release of the pressure occurs. When the pressure in the cylinder chamber exceeds this limit, the disk fails, releasing the pressure and thereby extinguishing the flame of the burning powder. Ignition is accomplished by means of a heating coil packed in black powder lying against the powder grain, the lead wires passing through a special fitting in the pressure gage adapter.

With this tester, the partially burned sample of powder usually is ejected by the exhausting gases, but can be recovered by having a canvas screen set up at a distance from the nozzle to prevent it from being lost or broken by impact.

It is, therefore, the purpose of this invention to provide certain improvements to the above described apparatus which will result in the unburned powder being retained intact within the tester after failure of the shear-disk.

The specific nature of the invention as well as other objects and advantages thereof will clearly appear from a description of a preferred embodiment as shown in the accompanying drawings in which:

Fig. 1 is a vertical longitudinal section through the testing device.

Fig. 2 is a vertical transverse section through the discharge nozzle.

Fig. 3 is an isometric view of the end portion of the spacer tube.

As shown in Fig. 1 the tester consists of a hollow cylinder 1 having an axial recess or combustion chamber 3, counterbored at one end as at 5 to form a shoulder 6. A thread 7 is provided in the counterbore 5 for threadably securing therein an adapter 12 for holding a conventional copper-ball pressure gage (not shown). An opening 9 through the other end of cylinder 1 is threaded as at 10 for receiving a conventional spark plug 31 for ignition purposes.

A radially disposed opening 18 is provided

2

through the wall of cylinder 1 opposite the mid-section of axial recess 3, a cylindrical extension collar 19, fillet welded to cylinder 1, serving to extend the opening 18 outwardly from cylinder 1.

5 An annular shear-disk adapter 20 is threadably secured in opening 18 adjacent the bottom thereof. A discharge nozzle 21 is provided for threadable assembly in opening 18, forming with shear-disk adapter 20 a discharge passage 23, opening radially outwardly from the middle of recess 3. A shear-disk 22 of the required thickness, depending on the pressure desired, is assembled between the shear-disk adapter 20 and the nozzle 21 and serves as a closure means to seal the passage 23 until such time as gas pressure developed in the tester rises to the required amount and causes shearing of the disk. Nozzle 21 has two sets of diametrically disposed wrench holes 24 by means of which a wrench bar (not shown) is used to tighten the nozzle and thereby lock the shear-disk 22 tightly in position, or to remove the nozzle in order to replace the disk.

25 A powder grain retainer or spacer tube 13 in the form of a rod or bar is provided having a generally cylindrical opening 14 extending longitudinally therethrough. This opening is of somewhat larger diameter than the powder grains to be tested and is provided to hold the powder grain to be tested in the combustion chamber 3 during 30 the test. Tube 13 has its longitudinal edges 15 rounded to produce a loose sliding fit of the tube 13 in recess 3 of cylinder 1. The ends of spacer tube 13 are slotted across the flats as at 16 to provide passage way for the gases being discharged 35 thereby providing sectionally equivalent passages from each end of cylindrical opening 14 for escape of burned powder gases to the centrally located discharge passage 23.

In operation, a single stick or grain of powder 40 30 is placed midway in opening 14 in spacer tube 13, opening 14 being of somewhat greater diameter than the grain of powder to be tested. Spacer tube 13 is then placed in recess 3 with one edge in alignment with the axis of discharge passage 23 and the pressure gage adapter 12 with a copper-ball gage (not shown) is screwed into position in the end, a gasket 25 serving to make a tight seal. A spark plug 31 is screwed tightly into opening 9 and has the space around its electrodes packed with a fine grade of black powder 45 as shown at 32.

A shear-disk 22 of the thickness required for the test is then secured against shear-disk adapter 20 by nozzle 21.

50 The tester is now ready to fire. A current of

the necessary voltage is passed through the spark plug 31 igniting the black powder 32 therein which in turn ignites the grain of smokeless powder. As soon as the pressure resulting from the combustion of the powder exceeds the shear strength of the shear disk, the disk blows out and the compressed gases around the powder grain inside of spacer tube 13 blow out through slots 16 in each end thereof, flowing along the flats of spacer tube 13 and passing out through discharge passage 23.

This sudden release of the pressure extinguishes the burning powder, the spacer tube 13 causing the powder gases to be drawing off equally from both ends of the powder sample instead of from a single end as in previous types of powder testers. The tendency for the partially burned sample of powder to be ejected when the shear-disk is blown out is thus entirely eliminated, and it is consequently retained intact for subsequent examination. The pressure developed may be measured by the deformation of a copper-ball suitably supported in adapter 12.

It is apparent from the above that the structure herein shown and described provides a means whereby the unburned portion of the powder will be retained intact within the tester after failure of the shear-disk.

I claim:

1. In a propellant powder tester of the type comprising an elongated hollow housing having at one end an ignition means, at the other end a force measuring means and a rupturable closure medially of the longitudinal extent of the housing, the improvement comprising a hollow elongated specimen holder received in the hous-

ing, its exterior defining, with the interior of the housing free longitudinal passages for the transmission of gases from the ends of the holder to the said closure.

5. 2. A tester, as in claim 1, said holder having kerfs in the end faces.

3. In a propellant powder tester of the type comprising an elongated housing having a bore of circular section and having at one end an ignition means, at the other end a force measuring means and a rupturable closure medially of the longitudinal extent of the housing, the improvement comprising an elongated specimen holder with a longitudinal, through opening received in the housing, said holder having a cylindrical exterior of cross-section departing from circularity whereby longitudinal passages are defined between the holder and the said bore for pressure communication between the inside of the holder and the said rupturable closure.

4. A tester, as in claim 3, said holder having kerfs in the end faces.

5. A tester, as in claim 3, the outer cross-sectional profile of said holder being polygonal.

ALFRED AFRICANO.
